(57) **ABSTRACT**

Systems and methods for operating a controlled device via an activation accessory of a wearable device that includes a movable actuator, a sensor, and a communication element. The sensor is coupled to a controller, which has an output coupled to a control signal interface. The controller is programmed to receive and evaluate input signals from the sensor that are responsive to movements of the movable actuator to determine whether or not they represent a command for the controlled device by assessing the input signals for a signal pattern indicative of a plurality of volitional actions of a wearer of the activation accessory. If/when the processor determines that the input signals represent the command, then it decodes the command and transmits an associated control signal to the controlled device via the control signal interface.

SWITCH SYSTEM FOR OPERATING A CONTROLLED DEVICE

RELATED APPLICATIONS

This is a NONPROVISIONAL of, claims priority to, and incorporates by reference U.S. Provisional Application Nos. 63/110,463, filed 6 Nov. 2020, and 63/260,499, filed 23 Aug. 2021, and is a CONTINUATION-IN-PART of and incorporates by reference U.S. application Ser. No. 17/247,976, filed 4 Jan. 2021, which claims priority to U.S. Provisional Application Nos. 62/705,524, filed 2 Jul. 2020, and 63/110,463, filed 6 Nov. 2020.

FIELD OF THE INVENTION

The present invention relates to systems and methods for operating a controlled device.

BACKGROUND

The desire for hands-free operation of controlled devices arises in many contexts. For example, U.S. Pat. No. 7,184,903 describes a hands-free, mouth-activated switch disposed within a cup-shaped, rigid portion of a pilot's oxygen mask. Among the elements controllable by such a switch is a night vision compatible light. U.S. Patent Application Publication 2012/0229248 describes a hands-free controller that monitors facial expressions of a wearer and other body motions and generates commands for a controlled device based on the combination of the facial expressions and other monitored motions.

SUMMARY OF THE INVENTION

Embodiments of the invention include systems and methods for operating a controlled device via an activation accessory of a wearable device that includes a movable actuator having a range of travel between a fully extended position and fully compressed position, a sensor, and a communication element. The sensor is coupled to a controller, which has an output coupled to a control signal interface. The controller is programmed to receive and evaluate input signals from the sensor that are responsive to movements of the movable actuator to determine whether or not they represent a command for the controlled device by assessing the input signals for a signal pattern indicative of a plurality of volitional actions (e.g., jaw clenches) of a wearer of the wearable device. If/when the processor determines that the input signals represent the command, then it decodes the command and transmits an associated control signal to the controlled device via the control signal interface.

In one example, the activation accessory of the wearable device includes a Hall effect sensor, and a magnet is positioned on the movable actuator so that it causes the Hall effect sensor to output signals to the controller due to movements of the movable actuator. The controller includes a processor and a memory coupled thereto which stores processor-executable instructions that, when executed by the processor, cause the processor to receive and evaluate input signals from the Hall effect sensor. In particular, the controller evaluates the input signals to determine whether or not they represent a command for the controlled device by assessing the input signals for a signal pattern indicative of any of a plurality of such commands. If/when the processor determines that the input signals represent one of the plurality of commands, then it decodes the respective command

and transmits an associated control signal to the controlled device via the control signal interface. The controller may also provide feedback to the wearer by providing an activation signal to a vibration motor. On the other hand, if the processor determines that the input signals from the sensor do not represent a command, no control signal or activation signal is transmitted and the processor proceeds to evaluate further/new input signals from the Hall effect sensor in a like manner as the original input signals.

10 A communication element, which may be a part of the activation accessory or otherwise included/integrated in the wearable device, is coupled to the control signal interface and is adapted to transmit the control signal from the processor to the controlled device. For example, the communication element may be a cable having a plug configured to mate with a jack at the controlled device, or a transmitter adapted for radio frequency communication with a receiver at the controlled device.

15 In various embodiments, the movable actuator may be supported in or by a mount on the wearable device, such as a temple piece or the frame of eyewear (e.g., glasses, goggles, AR/VR headset, etc.), a headset, or another arrangement. For example, the movable actuator may be movable with respect to a temple piece or frame of the eyewear, or a frame of a headset, so as to permit operation of the activation accessory at different positions on the wearer. In one example, the movable actuator of the actuation accessory may be positioned on the movable device so that when the movable device is being worn the movable actuator touches the skin of the wearer overlying an area of the wearer's temporalis muscle, or the tendon which inserts onto the coronoid process of the mandible, or masseter muscle. The temporalis muscle and masseter muscle can generally be felt contracting while the jaw is clenching and unclenching, and it is such clench actions which, by virtue of the resulting movement of the movable actuator, can cause the sensor to output signals to the controller.

20 In some cases, the movable actuator of the activation accessory may be supported in a helmet or mask (e.g., a helmet or mask used by a firefighter, a diver, an aircrew member, or another wearer), where the mask is configured to position the movable actuator so as to be overlying an area of the wearer's temporalis or masseter muscle. Alternatively, the entire activation accessory may be included in a module having an adhesive applied to a surface thereof to enable a module encasing the activation accessory to be worn directly on the face or head of the wearer. Such an adhesive may, in one case, be in the form of a removable film adhered to the surface of the module that encloses the activation accessory.

25 30 35 40 45 50 55 60 65 The activation accessory may include more than one Hall effect sensor, and/or sensors of different types, with the multiple sensors arranged with respect to one another so as to permit individual and/or group activation thereof by associated volitional jaw clench (or other muscle activity) actions of the wearer. Further, in addition to a vibrational motor, a visual activation indicator may be present. Such a visual activation indicator (e.g., an LED) may be coupled to receive a visual activation indication signal from the controller and the processor-executable instructions, when executed by the processor, may further cause the processor to perform transmit the visual activation indication signal to the visual activation indicator if/when the processor determines that input signals from one or more of the sensors represent a command for the controlled device.

When assessing the input signals from a Hall effect sensor or other sensor for the signal pattern indicative of a command for the controlled device, the processor may evaluate

the input signals against a stored library of command signal representations, where each command signal representation characterizes an associated command for the controlled device. Alternatively, or in addition, the input signals may be assessed according to respective power spectral densities thereof within specified time periods. Or the input signals may be assessed according to count values of the Hall effect sensor(s) received within a specified time period. Still further, the input signals may be evaluated against a trained model of command signal representations, where each command signal representation characterizes an associated command for the controlled device.

These and still more embodiments of the invention are described in detail below with reference to the accompanying drawings.

BRIEF DESCRIPTION OF THE DRAWINGS

The present invention is illustrated by way of example, and not limitation, in the figures of the accompanying drawings, in which:

FIG. 1 illustrates an example of an activation accessory for a controlled device configured in accordance with an embodiment of the present invention.

FIGS. 2A-2F illustrate examples of devices operated under the control of an activation accessory configured in accordance with an embodiment of the present invention.

FIG. 3 illustrates an example of an activation accessory secured in a headset mount configured in accordance with an embodiment of the present invention.

FIG. 4 illustrates an example of an activation accessory secured in a helmet in accordance with an embodiment of the present invention.

FIG. 5 illustrates an example of an activation accessory having a film of adhesive on one surface for attachment to a wearer.

FIG. 6 illustrates an example of an activation accessory secured in a temple piece of eyewear.

FIG. 7 illustrates an example of an activation accessory for a controlled device configured with multiple Hall effect sensors, in accordance with an embodiment of the present invention.

FIG. 8 illustrates an example of an input signal received by a processor of a wearable module from Hall effect sensor of the wearable module in accordance with embodiments of the present invention.

FIG. 9 illustrates a method of operating a controlled device in a hands-free manner through volitional jaw clench actions of a wearer in accordance with an embodiment of the invention.

FIGS. 10A-10D illustrate various examples of movable actuator and sensor arrangements for activation accessories configured in accordance with embodiments of the present invention.

DETAILED DESCRIPTION

Described herein are systems and methods for switched operation, in many cases hands-free operation, of controlled devices, for example illumination systems, push-to-talk systems, computer user interface cursors and other user interface elements, and other devices. These systems and methods are characterized, in part, by a wearable device, such as eyewear (e.g., glasses, AR/VR headsets, goggles, etc.), earphones, headphones, audio headsets, masks, helmets, headbands, garments, hats, caps, modules, etc., that are configured with an activation accessory for a controlled

device and a communication element coupled to the activation accessory. The communication element may be a component of the activation accessory or a separate component. The activation accessory generally includes a movable actuator having a range of travel between a fully extended position and fully compressed position and configured to be positioned in and to maintain the fully extended position until acted upon by a force, e.g., by a spring bias, a hinge, or other means. The activation accessory is positioned on or in the wearable device so that when the wearable device is worn the movable actuator of the activation accessory presses against the skin of the wearer, preferably overlying the wearer's temporalis muscle, the tendon which inserts onto the coronoid process of the mandible, or masseter muscle. In other instances, the activation accessory may be positioned on or in the wearable device so that when the wearable device is worn the movable actuator of the activation accessory presses against the skin of the wearer overlying a different muscle or tendon. For convenience, the reminder of the discussion below refers to the movable actuator of the activation accessory being positioned so as to overlie the wearer's temporalis muscle so as to be responsive to jaw clenches of the wearer, but readers should recognize this is only for convenience in explaining aspects of the invention and other positionings of the movable actuator of the activation accessory, through wearing of wearable devices on parts of the body other than the head or face so that the movable actuator is responsive to volitional movements of other muscles (e.g., those lying under areas of the body where the movable actuator would be adjacent to), are contemplated.

When the wearable device is worn so that, for example, the movable actuator of the activation accessory is positioned so as to overlie the wearer's temporalis muscle so as to be responsive to jaw clenches or other jaw movements of the wearer, hands free activation, deactivation, and/or operation of one or more controlled devices is possible. For example, to activate, deactivate, and/or operate a controlled device that is communicably coupled to the activation accessory, e.g., via the communication element, the wearer of the wearable device can perform one or more jaw clench actions. By clenching and unclenching his/her jaw, the wearer's temporalis muscle will be engaged and will expand and contract in the region of the wearer's temple. Because the movable actuator of the activation accessory on/in the wearable device is positioned so as to overlie the wearer's temporalis muscle in the region of the wearer's temple, when the wearer's temporalis muscle expands and contracts in accordance with the wearer's jaw clench actions, the movable actuator, which presses on the skin of the wearer in the temple region, is moved. In one example, a jaw clench or movement causes the movable actuator to move laterally with respect to the wearer and a jaw unclenching or other movement causes the movable actuator to move medially with respect to the wearer. Other motions of the movable actuator, such as rotations, may also be invoked through muscle movement. As described below, these movements of the movable actuator are registered by a sensor associated with the movable actuator and recognized as commands for the controlled device. Once so recognized, the commands are issued to the controlled device via the communication element. For the remainder of the discussion, jaw clenching and unclenching will be described, however, other movements of the jaw, for example lateral-medial movements, are contemplated for actuation of a movable actuator and have proved to be useful when positioning such actuators over a wearer's masseter muscle. Lateral-medial movements,

clenching and unclenching, and other jaw movements that result in flexing and relaxing of a wearer's masseter and/or temporalis muscle are contemplated and are generally referred to herein as volitional movements. Similarly, for movable actuators positioned overlying other muscles of a wearer, a variety of volitional movements may be used to manipulate the movable actuator of an activation accessory configured in accordance with the present invention.

In addition to this hands-free operation of the controlled device (in the above example, only a jaw clench/unclench action was used to provide a command to the controlled device), the same activation accessory can be used to activate, deactivate, and/or control the controlled device via touch actions of the wearer. For example, considering the same activation accessory on/in the wearable device with the movable actuator of the activation accessory positioned so as to overlie the wearer's temporalis muscle in the region of the wearer's temple as in the above example, the wearer may cause the movable device to move with respect to its associated sensor by touching/pressing the wearable device instead of by clenching/unclenching his/her jaw. If say the wearable device were eyewear and the movable actuator were positioned along one of the temple pieces of the eyewear so as to contact the wearer's skin in the region of the wearer's temple, then when the wearer pressed the temple piece of the eyewear towards his/her head (i.e., moved the temple piece medially towards his/her head), the movable actuator would move with respect to its sensor and cause the sensor to produce a signal just as if the movable actuator had moved responsive to a jaw clench. And, when the wearer released the temple piece of the eyewear and the temple piece of the eyewear moved laterally away from the wearer's head, the movable actuator would return to its original position with respect to the sensor, still touching the wearer's skin in the region of the wearer's temple, but now extended from the position it was in when the wearer was pressing on the temple piece. This touch/press responsiveness of the activation accessory in addition to its responsiveness to hand-free actions of the wearer provides a very versatile set of operating characteristics for the activation accessory of the wearable device and a wide range of potential operating commands for the controlled device could be made up of successive hands-free/touch-press actions of the wearer.

As noted, the sensor or sensors of the activation accessory is/are responsive to movements of the movable actuator. One such sensor is a Hall effect sensor that is responsive to movements of a magnet in the movable actuator. Other sensors could be used and several examples are discussed below. The sensor is communicably coupled to a controller of the activation accessory (or another controller that is included in the wearable device), and the controller has an output coupled to a control signal interface. Generally, the controller may include a processor and a memory coupled to the processor, which memory stores processor-executable instructions that, when executed by the processor, cause the processor to perform various operations. For example, the stored processor-executable instructions, when executed by the processor, may cause the processor to receive, from the one or more sensors, input signals that are produced as outputs of the sensor(s) responsive to movements of the movable actuator. The instructions may cause the processor further to evaluate the input signals to determine whether or not the input signals represent a command for said controlled device. Since the activation accessory is part of or attached to a wearable device, it is conceivable that some motion of the movable actuator, and, hence, some signals

output by the sensor(s) to the processor of the controller, may be associated with movements of the wearer that are not intended as movements representing commands for the controlled device. An example might be the wearer talking or eating. Such actions can be expected to cause the wearer's temporalis muscle to expand and contract, thereby causing a movable actuator positioned so as to be overlying the wearer's temporalis muscle in the region of the wearer's temple to move. This movement of the movable actuator would, in turn, cause the associated sensor(s) to produce output signals to the processor of the controller, but those signals should not cause the processor to issue commands to the controlled device because the wearer's movements were not intended to be interpreted as such commands. To address this situation and mitigate the effect of such movements of the wearer vis-à-vis commands issued to the controlled device, a filtering and/or analysis process may be used by the controller to distinguish volitional actions of the wearer that are intended as commands from those which are not.

Examples of the filtering and analysis process may include such things as band-pass filtering of the signals output by the sensor(s) so as to prevent high and/or low frequency signals, associated with high and/or low speed movements of the movable actuator, from being interpreted as signals associated with commands. Signals of a relatively high frequency may be regarded as being associated with rapid movements of the movable actuator, which may be indicative of movements of the wearer's jaw or other muscle when engaged in activities not associated with issuing commands for a controlled device (e.g., eating, talking, etc.). Similarly, relatively low frequency signals may be regarded as being associated with relatively slow movements of the movable actuator, which may be indicative of movements of the wearer's jaw or other muscle when engaged in activities not associated with issuing commands for a controlled device (e.g., stretching). By filtering out such relatively high and/or low frequency signals before they are provided to the processor of the controller for analysis (or by filtering of such relatively high and/or low frequency signals by the processor as a first step in any analysis), the present invention can avoid the issue of unintended commands to the controlled device.

Other actions in place of or in addition to this kind of filtering can be employed. For example, a microphone could be used in conjunction with the activation accessory (or as part thereof) and signals produced by the microphone when the wearer of the activation accessory is speaking provided to the processor. The stored processor-executable instructions, when executed by the processor, may be such that the processor, upon recognizing that the wearer is speaking, may ignore signals from the sensor(s) associated with the movable actuator as any such signals are likely to be the result of movement of the wearer's temporalis muscle (and, hence, the movable actuator) due to such speaking and not the result of the wearer issuing a command for the controlled device. Of course, the processor could be programmed so as to search for special signal patterns that indicate command sequences even when speaking is detected so that the activation accessory can be used to activate, deactivate, and/or control a controlled device even when the wearer is engaged in a conversation.

Further, and as discussed in greater detail below, the stored processor-executable instructions, when executed by the processor, may cause the processor to assess the input signals from the sensor(s) for one or more signal patterns indicative of a command for a controlled device, for example, by comparing time domain or frequency domain

representations of such signals to a stored library of command signal representations. By digitizing and then transforming received input signals from the sensor(s) using a Fast Fourier Transform algorithm, the processor may compare patterns of received input signals to stored replicas of known command clench and/or touch/press operations of the activation accessory and issue commands to the controlled device accordingly.

If the processor determines that the input signals from the sensor(s) represent a command for the controlled device, then the stored processor-executable instructions, when executed by the processor, may cause the processor to decode the command and, subsequently, transmit an associated control signal to the control signal interface. Otherwise, if the processor determines that the input signals from the sensor(s) do not represent a command for the controlled device, then the stored processor-executable instructions, when executed by the processor, will cause the processor to not transmit such a control signal and instead to proceed to evaluate further or new input signals from the sensor.

The communication element, which may be part of the activation accessory or another component of the wearable device, is coupled to the control signal interface and is adapted to transmit control signals from the processor to the controlled device. For example, the communication element may be a simple a cable having a plug configured to mate with a jack at the controlled device. Or the communication element may be a transmitter adapted for radio frequency communication with a receiver at the controlled device. Any of several kinds of radio frequency communications may be used, for example, Bluetooth, Bluetooth Low Energy (BLE), Zigbee, infrared, WiFi HaLow (IEEE 802.22h), Z-wave, Thread, SigFox, Dash7, or other form of radio frequency communication.

As noted, the activation accessory may be integrated into or attached to a wearable device such that when the wearable device is worn on a person the movable actuator of the activation accessory is touching the person at an area overlying the person's temporalis or masseter muscle. Such a wearable device may be a headset, in which case the movable actuator is preferably movable with respect to a portion of the headset, eyewear, in which case the movable actuator may be supported in a temple piece or a frame of the eyewear, or other device, garment, module, or accessory, as described herein.

In further embodiments, the present invention provides a wearable sensor module configured to detect muscle movement of a wearer and to control an electronic device (e.g., an illumination element, etc.). In some cases, the electronic device may be a wearable device that incorporates or includes the wearable sensor module or to which the wearable sensor module is attached. In other cases, it may be a device remote from the wearable sensor module.

The wearable sensor module has a movable control portion and a detection portion. The movable control portion has a defined range of travel in relation to the detection portion between a fully extended position and a fully seated position. In some instances, the movable control portion may be biased (e.g., by a spring, hinge, or other arrangement) so as to maintain its fully extended position until compressed towards its fully seated position by an outside force. When worn, the wearable sensor module contacts the wearer so that the movable control portion partially compresses. This partial compression results in the detection portion producing an initial signal; for example, upon the wearer donning the wearable sensor module, the detection portion may produce the initial input signal as a result of

movement (compression) of the movable control portion when coming into contact with the wearer's body in a region overlying the wearer's temporalis muscle (e.g., at or near the wearer's temple). The initial signal may cause the wearable sensor module to wake from a sleep or inactive state so that subsequent movements of the movable control portion caused by flexing and relaxing of the wearer's muscle(s) over which the sensor module is positioned cause the sensor to produce further signals that, when recognized by a controller of the wearable sensor module or the wearable device in which it is instantiated or to which it is attached, result in commands for controlling the electronic device to be generated.

The detection portion of the wearable sensor module is preferably configured to detect varying degrees of movement of the movable control portion, which varying degrees of movement result in commands for controlling the electronic device to be generated. That is, it is recognized that the wearable device in which the wearable sensor module is instantiated or to which it is attached may be worn by different individuals, some or all of which may have heads of different shapes and sizes. So, the movable control portion of the wearable sensor module may be actuated to different degrees by the different wearers. The detection portion is arranged and situated with respect to the movable control portion so as to be responsive to these different degrees of actuation of the movable control portion, e.g., different lengths of travel or movement thereof due to jaw clenching or other muscle movement.

As mentioned, when the movable control portion is not experiencing any external forces acting upon it, it is biased open from the detection portion, e.g., by a hinge or layer of over-molded elastic polymer that provides spring-like bias. Then, when the movable control portion contacts the wearer, e.g., being donned by the wearer, it is partially compressed along its length of travel with respect to the detection portion. This may happen, for example, when the movable control portion contacts an area of the wearer's head or face overlying the temporalis muscle or overlaying the masseter muscle.

The detection portion of the wearable sensor module may be removably attached or slidably attached to the wearable electronic device. Such configurations may allow for replacement of broken or damaged detection portions. Alternatively, the detection portion is integrated as part of the wearable electronic device or of the wearable device to which the wearable electronic device is attached. And, as described above, input actuations of the movable control portion may be generated both in a hand-free manner and/or manually by tapping or pressing the wearable electronic device to cause the movable control portion to compress against or extend away from an area of the body over which the wearable sensor module is positioned. The wearable sensor module is thus configured to detect the movement of the movable control portion as having been affected by tapping or pressing on the medial or lateral side of the wearable electronic device when the wearable electronic device is being worn.

In still further embodiments, the present invention provides a wearable sensor module configured to detect muscle movement and to control an electronic wearable device while attached thereto. The wearable sensor module has a movable control portion, movement of which may be effected by a wearer of the electronic wearable device flexing and/or relaxing his/her temporalis and/or masseter muscle, and a detection portion, which may be attached to the wearable electronic device by an adjustable mounting

interface. The movable control portion has a defined range of travel in relation to the detection portion, between a fully extended position (in which the movable control portion is biased when not acted upon by any external forces) and a fully seated position. Accordingly, the movable control portion maintains its fully extended position with respect to the detection portion unless or until compressed towards its fully seated position by an outside force. When worn by a wearer, the wearable sensor module contacts the wearer so that the movable control portion partially compresses, establishing an initial signal by the detection portion, for example upon the wearer donning the wearable sensor module. The initial signal and subsequent outputs of the detection portion being effected by movement of the movable control portion caused by coming into contact with the person of the wearer and thereafter flexing and relaxing of muscles associated with volitional jaw movements of the wearer. The initial signal established as a result of partial compressing of the movable control portion when the wearer dons the wearable sensor module is generated at a point at which the movable control portion is positioned at location between its fully extended position and fully seated position so as to provide for subsequent adequate movement of the movable control portion with respect to the detection portion in order to generate commands for a controlled device upon the position of the movable control portion being affected by volitional jaw movements of the wearer.

Activation elements of wearable devices configured in accordance with embodiments of the present invention may be employed in combination with eyewear (e.g., eyeglasses, goggles, AR/VR headsets, etc.), headsets, masks, garments, accessories, or other head/face-worn articles used in a variety of contexts, including military, law enforcement, health care, and others (e.g., consumer). The head/face-worn article positions the movable actuator of the activation element so that it overlies an area of the wearer's temporalis muscle so that clenching/flexing of the wearer's jaw moves the movable actuator with respect to the sensor, thereby allowing for hand-free operation of the controlled device. Other embodiments of the invention make use of the movable actuator as part of other head-worn articles, including but not limited to illumination, imaging, and/or communication systems. In some instances, the movable actuator may be positioned in locations other than over the wearer's temporalis muscle, allowing activation/deactivation/operation of controlled devices by means of muscles associated with a wearer's eyebrow, jaw, or other body part.

As used herein, when referencing an area of a wearer's head or face overlying the temporalis muscle, we mean that movable actuator is positioned to contact the right or left side of the wearer's head or face within an area generally behind the eye and forward of the ear, near an area where the frontal, parietal, temporal, and sphenoid bones of the skull fuse. In other cases, for example where the movable actuator is positioned by a headset or similar arrangement, it may be positioned above the wearer's ear. The movable actuator is responsive to a relaxed condition and a flexed condition of the wearer's jaw, that is, it is movable with respect to the sensor responsive to the user clenching and unclenching his/her jaw, thereby allowing the wearer to generate input signals for operating/activating/deactivating controlled devices, such as electronic system components, via such clench actions. Note that while much of the discussion herein refers to actions of a wearer's jaw, such as clenching/unclenching, activation elements configured in accordance with embodiments of the present invention may be employed in connection with other volitional acts of a user

moving his/her muscles. Also, while jaw clenches/unclenches are a preferred form of manipulation of a movable actuator, hand/finger presses can also be used. For example, in the case of an activation element mounted on eyewear or a headset, a hand/finger press on the outside of the eyewear temple piece or earphone cup may cause the movable actuator to move with respect to the sensor of the activation element, resulting in signals being provided from the sensor to the controller of the activation element for operation/deactivation of the controlled device.

The support for the activation element may be adjustable in terms of the positioning of movable actuator so that it overlies a portion of the wearer's temporal muscle. Further, the movable actuator may be arranged so as to be at its fully extended position when the activation element is not being worn. For example, the movable actuator may include a spring or hinge that is biased so as to be extended or open when the activation element is not being worn. Then, when a user dons the activation element, e.g., by putting on eyewear or a headset that includes the activation element, the movable actuator may be partially compressed or moved, e.g., by contacting the wearer's head or face, to a semi-closed position between its fully extended position and fully compressed position. This movement of the activation element with respect to the sensor may cause the sensor to issue an output signal which the controller may interpret as a wake-from-sleep or similar command to begin sampling the sensor output for possible controlled device command signals.

The use of "clench interactions" has been recognized as a viable control technique. For example, the present applicant's U.S. PGPUB 2020/0097084, Xu et al., "Clench Interaction: Novel Biting Input Techniques," Proc. 2019 CHI Conference on Human Factors in Computing Systems (CHI 2019), May 4-9, 2019, Glasgow, Scotland UK, and Koshnam, E. K. et al., "Hands-Free EEG-Based Control of a Computer Interface based on Online Detection of Clenching of Jaw," in: Rojas I., Ortúñoz F. (eds) Bioinformatics and Biomedical Engineering, IWBBIO 2017, pp. 497-507 (Apr. 26-28, 2017) all provide examples of such techniques. In Xu et al., the use of bite force interfaces may afford some advantages in some applications, however, the present invention adopts a different approach inasmuch as it relies on sensors placed outside a user's oral cavity. Such sensors are more suitable for applications where the presence of sensors inside one's mouth may be uncomfortable or impractical. In Koshnam et al., the EEG sensors were external to the oral cavity, having been placed at temporal sites T7 and T8 on the wearer's head, but there was no provision for alerting the wearer when a command signal was recognized as having been initiated through a jaw clench action. Accordingly, the system was perceived as having excessive lag time in recognizing and implementing a clench action, which adversely impacted its use as a control element for a remote device.

Referring to FIG. 1, an example of an activation accessory 10 for a controlled device is shown. In some embodiments, the controlled device may be a wearable device in which the activation accessory is incorporated or attached to. In other cases, the controlled device may be remote from the activation accessory. The activation accessory 10 includes a vibration motor 12, a module 14 that includes a movable actuator 8, a Hall effect sensor 16, and a controller 18. Hall effect sensor 16 is responsive to movements of the movable actuator 8 (e.g., one or more magnets included in or on the movable actuator 8) and is communicably coupled to controller 18 through an analog-to-digital converter 20, which

converts the analog output of the Hall effect sensor 16 to a digital signal that is provided as an input to a processor 22 of the controller. Processor 22, in turn, has outputs coupled to a control signal interface 24 and the vibration motor 12.

Examples of movable actuators and sensors are further illustrated in FIGS. 10A-10D. In FIG. 10A, the movable actuator 8 is a lever arm that is biased open with respect to sensor 16 by a spring 9 so as to be extended or open when the activation element is not being worn. In FIG. 10B, the movable actuator 8 is an over molded elastomer member that is supported on a pliable gasket or similar joint 11 and the sensor 16 is an optical sensor that produces an output signal responsive to movements of the movable actuator 8 towards and/or away from the sensor. In FIG. 10C, the movable actuator 8 is biased in an open position with respect to sensor 16 by one or more springs 13. When acted on by a force (e.g., a muscle movement due to a jaw clench or a touch/press), the movable actuator 8 moves towards the sensor 16, causing the U-shaped leaf 15, which may be made of spring steel or another conductive material) to contact sensor 16, resulting in sensor 16 producing an output signal. The sensor 16 may be force-sensitive so that the magnitude of the output signal is responsive to the pressure exerted upon it by the U-shaped leaf 15; thus, an initial pressure due to a wearer donning the wearable module or a wearable device in which it is included or attached may cause the sensor 16 to output a signal of a magnitude indicative of a wake signal, while subsequent pressures due to jaw clench actions and/or touch/press actions of the wearer may cause the movable actuator 8 to further compress the U-shaped leaf 15, resulting in greater pressure on sensor 16 and causing sensor 16 to output signals of a magnitude indicative of control inputs for the controlled device. FIG. 10D illustrates the movable actuator 8 as a lever arm that is biased open with respect to sensor 16 by a living hinge 17 so as to be extended or open when the activation element is not being worn.

Other sensors that can be used include fiber optic compression sensors in which the illuminance of photonically energized fiber optic cable as detected by a photosensor is varied according to the compression of a sleeve or other attenuator surrounding or enclosing the fiber optic cable (e.g., by the action of a movable actuator responsive to jaw clench or other muscle movements of a wearer). Photosensor output is analyzed and processed as an input command for controlling electronic devices in the manner described herein. Such a sensor/controller arrangement is very lightweight and unobtrusive, requires no electronic components (and so is highly rugged/waterproof), features low-compute signal processing, provides variable input and is very low cost. The sensor's actuator can be placed away from the light source and photosensor expanding design flexibility. The sensor/controller could be positioned on eyewear and actuated by the temporalis muscle via jaw clenching to control electronic devices or positioned over other areas of the body to provide hands-free input by detecting movement. For example, one or more sensors could be attached to a glove and positioned over one or more knuckle bones in order to detect grasping/clenching. As the glove tightens over the knuckles while grasping/clenching, photonic output from the fiber optic cable would be reduced and detected by the photosensor, resulting in input commands being generated.

The processor 22 of controller 18 is also coupled to a memory 26, which stores processor-executable instructions that, when executed by processor 22, cause processor 22 to receive and evaluate input signals from the Hall effect sensor 16. Controller 18 (i.e., processor 22) evaluates the input

signals to determine whether or not they represent a command for the controlled device by assessing the input signals for a signal pattern indicative of such a command. As more fully discussed below, if/when the processor 22 determines that the input signals from Hall effect sensor 16 represent the command for the controlled device, then processor 22 decodes the command and transmits an associated control signal to the controlled device (not shown in this view) via the control signal interface 24, and optionally transmits an activation signal to the vibration motor 12. On the other hand, if the processor 22 determines that the input signals from Hall effect sensor 16 do not represent the command for the controlled device, no control signal or activation signal is transmitted and processor 22 proceeds to evaluate further/new input signals from the Hall effect sensor 16 in a like manner. In one embodiment, the activation signal for the vibration motor is a pulse width modulated signal. The haptic feedback provided by vibration motor 12 may also be activated by another user (e.g., through a communication to the wearer of activation accessory 10) to provide a means for silent communication.

Referring now to FIGS. 2A-2F, various examples of controlled devices and arrangements for communicatively coupling same to the activation accessory 10 are shown. As mentioned, the controlled device may be (or be a part of) a wearable device in which the activation accessory is incorporated or attached to. In FIG. 2A, the controlled device is an illumination element 30 made up of one or more LEDs 32. As indicated above, the processor of controller 18 is coupled to the control signal interface 24 and is adapted to transmit a control signal to the controlled device, in this case illumination element 30, via the control signal interface 24. Not shown in the illustration are drivers and other interface elements that may be present to amplify and/or otherwise condition the control signal so that it is suitable for use with the illumination element 30.

FIG. 2B illustrates an example in which the activation accessory 10 is coupled to a transmitter 34 via the control signal interface 24. Transmitter 34 may be a low power/short range transmitter, such as a Bluetooth™, Bluetooth Low Energy (BLE), Zigbee, infrared, WiFi HaLow (IEEE 802.22h), Z-wave, Thread, SigFox, Dash7, or other transmitter. The transmitter 34 may itself be the controlled device or, alternatively, as shown in FIG. 2D, the transmitter 34 may be one component of a wireless communication system that includes a receiver 36 communicatively coupled to a controlled device, such as two-way radio 38. In such an arrangement, transmitter 34 is adapted for radio frequency communication with receiver 36 at the controlled device. Thus, the control signal issued by processor 22 of controller 18 is coupled to the control signal interface 24 and transmitted via a radio frequency signal from transmitter 34 to the controlled device.

FIG. 2C shows a further alternative in which the activation accessory 10 is coupled directly to two-way radio 36. In this example, the control signal interface 24 may be coupled to the two-way radio 36 by a cable having a plug configured to mate with a jack at the two-way radio 36 (or, more generally, the controlled device). As such, the activation accessory 10 may function as a push-to-talk (PTT) unit for the two-way radio 36. Or, as shown in FIGS. 2E and 2F, the activation accessory 10 may function as an ancillary PTT element for a PTT adapter 40 for the two-way radio 36. The connection between the activation accessory 10 (control signal interface 24) and the PTT adapter 40 may be wired, as shown in FIG. 2E, e.g., using a cable having a plug configured to mate with a jack at the PTT adapter, or

wireless, using a transmitter/receiver pair 34, 36. Of course, other arrangements for communicating the control signal produced by the processor 22 (or, more generally, controller 18) of the activation accessory 10 to a controlled device may be used.

In addition to the above-described examples, the processor 22 may also communicate with and control other peripherals, such as a heads-up display, audio input/output unit, off-headset unit, etc. Processor 22 is a hardware-implemented module and may be a general-purpose processor, or dedicated circuitry or logic, such as a field programmable gate array (FPGA) or an application-specific integrated circuit (ASIC), or other form of processing unit. Memory 26 may be a readable/writeable memory, such as an electrically erasable programmable read-only memory, or other storage device.

Referring now to FIG. 3, in various embodiments, the activation accessory 10 may be supported in a mount 42 of a headset 44, or another arrangement. For example, such a mount 42 may be movable with respect to a frame of the headset or a component thereof, such as earcup 48, so as to permit locating the activation accessory 10 at different positions on the wearer. More generally, such a mount 42 may be configured to position the activation accessory 10 so as to be overlying an area of the wearer's temporalis muscle. As mentioned above, while jaw clenches/unclenches are a preferred form of manipulation of the movable actuator of activation accessory 10, hand/finger presses can also be used. For example, a hand/finger press on the outside of the earcup 48 may cause the movable actuator to move with respect to the sensor of the activation element 10, resulting in signals being provided from the sensor to the controller of the activation element for operation/activation/deactivation of the controlled device.

In some cases, as shown in FIG. 4, activation accessory 10 may be supported in a helmet 60, where the helmet 60 is configured to position the activation accessory 10 so as to be overlying an area of the wearer's temporalis muscle. In still other arrangements, activation accessory 10 may be supported in a mask (e.g., a mask used by a firefighter, a diver, an aircrew member, of another wearer), where the mask is configured to position the activation accessory 10 so as to be overlying an area of the wearer's temporalis muscle. Alternatively, as shown in FIG. 5, the activation accessory 10 may have an adhesive applied to a surface thereof to enable the activation accessory 10 to be worn on the face or head of the wearer. Such an adhesive may, in one case, be in the form of a removable film 54 adhered to the surface of the activation accessory 10.

FIGS. 3 and 4 also illustrate the use of activation accessories 19 positioned over a wearer's masseter muscle. This may be in addition to or in lieu of an activation accessory 10 positioned over the wearer's temporalis muscle. In FIG. 3, the activation accessory 19 may be supported in or on an extension 23 of headset 44, or another arrangement, to position the activation accessory 19 over the masseter muscle, that is positioned to contact the right or left side of the wearer's face within an area below the ear canal to the bottom of the mandible and extending forward beneath the zygomatic arch, which is formed between the zygomatic process of the temporal bone and the temporal process of the zygomatic bone, and the zygomatic bone. The active control surfaces of the activation accessory 19 are configured to detect a relaxed condition and a flexed condition of the wearer's masseter muscle, thereby allowing the wearer to generate input signals for controlling a controlled device via masseter muscle manipulation. For example, such an extension

23 may be movable with respect to the frame of the headset or a component thereof, such as earcup 48, so as to permit locating the activation accessory 19 at different positions on the wearer. More generally, such an extension 5 may be configured to position the activation accessory 19 so as to be overlying an area of the wearer's masseter muscle. In some cases, as shown in FIG. 4, the activation accessory 19 may be supported in a mask 27 (e.g., a mask used by a firefighter, a diver, an aircrew member, of another wearer), 10 where the mask is configurable to position the activation accessory 19 so as to be overlying an area of the wearer's masseter muscle. Masks, headsets, eyewear and other supporting articles for an activation accessory may further permit the use of two (or more) activation accessories by a 15 wearer, for example, one positioned on the left side of the wearer's head or face and the other positioned on the right side of the wearer's head or face. By providing both a left and right activation accessory (or any number of them) which may be configured to allow for input of various 20 command sequences (e.g., different numbers of activations similar to single-, double- or other mouse clicks), a wearer may provide different commands for an associated controlled device or multiple devices. For example, different command activation sequences may be used for zooming a 25 camera, panning a direction in a virtual/visual environment, or a host of other commands to control cameras, audio transmissions (volume up or down), etc. In addition to the foregoing, the use of gyros and/or accelerometers while clenching and holding can allow for selecting and moving 30 objects in a virtual field. This is similar to a click-and-hold followed by movement of a cursor with a mouse or joystick in that it allows a user to move objects (e.g., icons) around on a virtual desktop, to open menus, and to select commands, etc. by clenching and moving one's head. The gyros and/or accelerometers may be incorporated in wearable 35 module 14 or elsewhere (e.g., in a frame supporting the wearable module).

In still other embodiments, the activation accessory 10 may be supported on a temple piece of eyewear 64, as shown 40 in FIG. 6. In particular, the activation accessory 10 can be adhered to the inside of eyewear temple piece 66 or slipped over a temple piece and held by screws, in each case so as to allow the movable actuator to contact the wearer's temple area when the eyewear is worn. This also provides a convenient location for vibration motor 12. From this position 45 on the user, when the processor of activation accessory 10 detects volitional movements of the wearer's temporal muscle and issues subsequent command signals, e.g., for activating, deactivating, or controlling a controlled device (e.g., changing the volume of audio communications or 50 music, turning on integrated lighting modules, or answering a phone call), the vibration motor may be activated to provide feedback that indicates successful recognition of the input command. As discussed below, a distinct "clench 55 language" may be programmed to control certain functions of the controlled device using specific temporalis muscle clenches or patterns. The vibration motor may also provide haptic feedback to the wearer as notification of microphone status or other enabled systems. For example, 60 light vibrations of the vibration motor in a specific pattern may alert the wearer that a microphone is open, so as to prevent an "open-mic" situation where others are prevented from communicating over a common channel.

Further, additional sensors such as for wearer vital signs 65 monitoring may also be integrated into the temple 66 to provide remote biomonitoring of the wearer, as the temple area has been proven to be an effective location for sensing

certain vital signs. Such sensors may be integrated into the eyewear temples **66**, permanently attached as an accessory, or attached to the inside of the temple using adhesive tape, glue, magnets, hook and loop fasteners, screws, or a tongue and groove or dovetail profile connection mechanism. The sensor signal may be routed through a powered cable/tether or via a wireless connection such as Bluetooth or Near Field Magnetic Induction. In other embodiments, one or more biomonitoring sensors **65** may be integrated onto/into a movable actuator of the activation accessory **10**, for example at a point of contact between the movable actuator and the wearer's skin. FIG. 6 illustrates examples of such sensors.

The activation accessory **10** may include more than one Hall effect sensor **16**, with the multiple sensors arranged with respect to one another so as to permit individual and/or group activation thereof by associated volitional jaw clench actions of the wearer. For example, FIG. 7 illustrates activation accessory **10'** that includes two Hall effect sensors **16-1**, **16-2**. Each Hall effect sensor is associated with a respective paddle switch **56-1**, **56-2**, as an associated movable actuator. The paddle switches can be depressed through a volitional jaw clench action of the wearer. Depressing a paddle switch will cause its associated Hall effect sensor to be activated.

Further, as shown in FIGS. 1, 4, and 6, in addition to the vibrational motor **12**, a visual activation indicator **50** may be present. Such a visual activation indicator, e.g., one or more LEDs, may be coupled to receive a visual activation indication signal from the controller **18** (processor **22**) and the processor-executable instructions stored in memory **26**, when executed by processor **22**, may further cause processor **22** to transmit the visual activation indication signal to the visual activation indicator **50** so as to illuminate the one or more LEDs for a brief period of time if/when the processor **22** determines that the input signals from the Hall effect sensor **16** signals represent a command. As shown in the various illustrations, the visual activation indicator **50** may be located on a helmet **60** or an indicator panel associated therewith, or as an attachment, integral or otherwise, to a pair of glasses **64** or goggles, e.g., on the temple pieces **66** thereof. An activation indicator of this kind is especially useful when the activation accessory **10** is used to control devices such as PTT controllers/adapters associated with tactical radios or the radios themselves. When providing microphone actuation when using such radios, a "microphone status LED" may be included in visual activation indicator **50** to provide a visual awareness of microphone condition. This LED emits light inside of the eyewear **64** which is visible only by the wearer. This provides effective light discipline in the tactical situations. Light would be visible when the microphone is in use (i.e., open) and would be extinguished when the microphone is not in use (i.e., off).

In the various embodiments, activation accessory **10** is positioned so that the movable actuator contacts the wearer's head or face, over the temporalis muscle so that clenching/flexing of the jaw activates the Hall effect sensor **16**. Power supply and control electronics for the activation accessory **10** may be incorporated within the activation accessory **10** itself, and/or in a frame, helmet, or mask that supports the activation accessory **10** or elsewhere. In the arrangement shown in FIG. 3, the activation accessory **10** is mounted above the earphone cup **48** of headset **44** by means of a mount **42** but other arrangements may be used. In some embodiments, the activation accessory **10** may be attached to or integrated in a movable portion of mount **42** that is rotatable about a rivet, pin or other joint or hinge and may also be flexible so as to be moved adjacent to or away from

a wearer's face. This is useful to prevent unwanted actuations of Hall effect sensor **16**.

In the various embodiments, the movable actuator **8** may be hingibly attached to or within activation accessory **10**, for example by a spring-loaded hinge that keeps the movable actuator **8** against the wearer's head or face even when the wearer moves his/her head, unless moved away from the wearer's head/face by an amount sufficient to engage a detent that prevents return to a position adjacent a wearer's face unless manually adjusted by the wearer. Such a hingible arrangement may incorporate a spring-loaded hinge of any type, for example a spring-loaded piano hinge, butt hinge, barrel hinge, butterfly hinge, pivot hinge, or other arrangement. Other embodiments include the use of a living hinge or an elastic/memory effect produced by wholly or partially encapsulating the movable actuator in an over-molded elastic polymer which produces a stretchable membrane effect, and which also provides water resistance.

As should be apparent from the above discussion, use of the activation accessory does not require donning a headset or mask. Instead, the activation accessory can be worn by itself, e.g., through use of an adhesive. Incorporating the activation accessory in headsets would typically be the norm for any member of an aircraft flight or operations crew, but headsets such as the one illustrated in the above-referenced figures are not restricted to use by flight/aircraft crews and may be employed by ground forces, naval/coast guard personnel, and civilians. For example, headsets such as the ones described herein may be employed by workers in and around construction sites, sports arenas, film and television production locations, amusement parks, and many other locations. By employing headgear equipped with activation accessories such as those described herein, wearers thereof have ready access to activation/deactivation/operation of illumination, imaging, gaming, and/or communications system(s)) in a hands-free fashion. Note that although FIG. 3 illustrates a headset with both left and right earphone cups, this is for purposes of example only and the present system may be used with headsets having only a single earphone cup, or one or two earpieces. Indeed, the present system may be used even with headgear that does not include any earphones or earpieces, for example attached to a band worn on the head or neck, or on a helmet or other headgear.

When assessing the input signals from the Hall effect sensor(s) **16** for a signal pattern indicative of a command, the processor **22** may evaluate the input signals against a stored library of command signal representations, where each command signal representation characterizes an associated command for the controlled device. Alternatively, or in addition, the input signals may be assessed according to respective power spectral densities thereof within specified time periods. Or the input signals may be assessed according to count values of the Hall effect sensor(s) received within a specified time period. Still further, the input signals may be evaluated against a trained model of command signal representations, where each command signal representation characterizes an associated command for the controlled device.

An example of an input signal received by processor **22** from Hall effect sensor **16** is illustrated in FIG. 8. Trace **72** depicts "counts" of the Hall effect sensor **16** received by processor **22** over time. In this context, the counts, represent the applied magnetic field detected by the Hall effect sensor **16** which varies with the movement of the movable actuator **8** in response to jaw clench actions of the wearer. Other output parameters that can be measured to provide similar results include voltage and/or current. More generally, in

embodiments of the present invention the activation accessory **10** includes one or more switch elements (Hall effect sensor(s) **16** or other(s) of the sensors discussed herein) that is/are sensitive to movements of a wearer's temporalis muscle and which are communicatively coupled to controller **18** having processor **22** and memory **26** coupled thereto and storing processor-executable instructions. Processor **22** is further coupled to provide an output signal to an indicator, such as illumination element **50** and/or vibration motor **12**. The activation accessory **10** may be fitted to a head- or face-worn article (e.g., a garment, headset, mask, or eyewear, as described herein) so as to be capable of being positioned to allow the movable actuator(s) with the one or more switch elements to contact a side of the wearer's head or face. The processor-executable instructions stored in memory **26**, when executed by processor **22**, cause the processor to receive input signals from the one or more sensors, detect relaxed (signal level high in FIG. 9) and clenched (signal level low) conditions (e.g., by level or edge detection of the input signals) of the wearer's jaw. From these input signals, processor **22** decodes the relaxed and clenched conditions as commands (74, 76, 78, etc.) for controlling electronic system components communicatively coupled to the controller and alerts the wearer to successful decoding of the commands by providing the output signal to the indicator.

As illustrated in FIG. 8, trace **72** exhibits marked shifts in count values corresponding to periods of time when a wearer relaxes (signal level high) and clenches (signal level low) his/her jaw while wearing activation accessory **10**. The detection of such actions by processor **22** may be edge-sensitive or level-sensitive. Further, as indicated above, the Hall effect sensor signals may be decoded according to a clench language to discriminate between activation, deactivation, and operational commands for the controlled device. The example shown in FIG. 8 represents decoded signals representing commands for an illumination unit. Signal groups **74** and **78**, a short clench followed by a long clench, represent activation ("on") and deactivation ("off") commands. That is, the illumination module is ordered to change operating state, from a current state on or off to an opposite state off or on, respectively, when such a set of input signals is recognized by the processor **22**. Signal group **76** represents a command to alter an output characteristic, e.g., brightness, and corresponds to two short clenches followed by a long clench. The two short clenches signal a change in output and the long clench signals that the brightness of the illumination unit should be varied, e.g., low to high, during the period of the clench action. Of course, other clench languages for a variety of controlled devices may be implemented. For example, in addition to double clench inputs signaling a following command input, triple clench inputs may be recognized as signally valid command inputs, different from commands associated with a double clench input. Further multiple clench inputs and/or clench-and-hold inputs may also be recognized as signifying different commands. Such multi-clench inputs are useful for eliminating unintentional actuations of Hall effect sensor **16**, as may be occasioned by involuntary muscle movements or by a wearer chewing food, gum, etc., or clenching his/her jaw during other activities. Generally, the intended command may be identified by decoding the detected relaxed and clenched conditions of the wearer's jaw according to a clench language that identifies such commands according to a number of detected clench actions identified within a time period, for example, a number of detected short and long (clench-and-hold) clench actions identified within a time

period. Valid forms of clench inputs may be used to turn on/off lighting elements and/or individual LEDs thereof, adjust the intensity of one or more illuminated LEDs, or to signal other desired operations. In general, clench input actuation sequence timings, repetitions, and durations may each be used, individually and/or in combination to specify different command inputs for one or more controlled devices.

FIG. 9 illustrates a method **80** of operating a controlled device in accordance with embodiments of the present invention. At **82**, the controller **18** receives from the Hall effect sensor **16** in the wearable module **14** first input signals. At **84**, processor **22** of controller **18** evaluates the first input signals according to and by executing processor-executable instructions stored in memory **26** to determine whether or not the first input signals represent a command for the controlled device. As discussed above, this evaluation **84** proceeds by the processor assessing **86** the first input signals for a signal pattern indicative of a plurality of volitional jaw clench actions of a wearer of the activation accessory **10**. If processor **22** determines that the first input signals represent the command, step **88**, then processor **22** decodes the command **90**, e.g., by identifying the input signals as being one of a number of patterns of a clench language, as described above, and transmitting **92** an associated control signal to the controlled device via a communication element communicably coupled to the processor, and, optionally, transmitting **94** an activation signal to a vibration motor of the wearable module. As indicated above, the communication element may be a cable having a plug configured to mate with a jack at the controlled device, a transmitter adapted for radio frequency communication with a receiver at the controlled device, or other element. Decoding the command signal may involve determining the number of short clench actions preceding a long clench action to determine the nature of a following one or more long and/or short clench actions, and may also depend on a current operating state of the controlled device. Otherwise, step **96**, the processor **22** does not transmit the control signal and the activation signal and instead proceeds to evaluate second/next input signals **96** from the Hall effect sensor in a like manner as the first input signals.

In general, Hall effect sensor **16** is a device that requires little or no mechanical displacement of a control element associated with movable actuator **8** in order to signal or effect a change (or desired change) in state of a controlled system. Other examples of such a device which may be used in place of the Hall effect sensor **16** include an EMG sensor or a piezo switch, such as the Piezo Proximity Sensor produced by Communicate AT Pty Ltd. of Dee Why, Australia. Piezo switches generally have an on/off output state responsive to electrical pulses generated by a piezoelectric element. The electrical pulse is produced when the piezoelectric element is placed under stress, for example as a result of compressive forces resulting from movement of a movable actuator **8** responsive to a wearer clenching his/her jaw so that pressure is exerted against the piezoelectric element. Although the pulse is produced only when the compressive force is present (e.g., when the wearer's jaw is clenched), additional circuitry may be provided so that the output state of the switch is maintained in either an "on" or an "off" state until a second actuation of the switch occurs. For example, a flip-flop may be used to maintain a switch output logic high or logic low, with state changes occurring as a result of sequential input pulses from the piezoelectric element. One advantage of such a piezo switch is that there are no moving parts (other than a front plate that must

deform by a few micrometers each time a wearer's jaw is clenched) and the entire switch can be sealed against the environment, making it especially useful for marine and/or outdoor applications.

Another example is a micro tactile switch. Although tactile switches employ mechanical elements subject to wear, for some applications they may be more appropriate than Hall effect sensors or piezo switches because they provide mechanical feedback to the user (although the haptic feedback provided by vibration motor 12 also provides an acceptable level of feedback for a user and so may be sufficient in the majority of instances). This feedback can provide assurance that the switch has been activated or deactivated. Momentary contact tactile switches may also be used, but because they require continual force (e.g., as provided by clenching one's jaw against the switch), they are best suited to applications where only a momentary or short engagement of the active element under the control of switch is desired, for example, signal light flashes, burst transmissions, or other short duration applications, or where a flip flop is used to maintain an output state until a subsequent input is received, as discussed above. Other forms of switches include a ribbon switch (e.g., as made by Tapeswitch Corporation of Farmingdale, NY) and conductive printed circuit board surface elements activated via carbon pucks on an overlaid keypad.

Further, in various embodiments, the controlled device may consist of one or more LEDs, which emit light in one or more wavelengths. Further, the controlled device may include one or more cameras for digital still and/or video imaging. In some instances, a lighting element may be worn on one side of the headset while an imaging system is worn on the opposite side, each being controlled by separate activation accessories mounted on respective opposite sides of the headset, or by activation accessory if the lighting and illumination systems are responsive to different command signals, similar to the way in which computer cursor control devices (e.g., touch pads, mice, etc.) may be separately responsive to single, double, triple, or other multiple clicks. Indeed, the activation accessory may itself be used to control a cursor as part of a user-computer interface. For example, any or all of cursor type, cursor movement, and cursor selection may be controlled using an activation accessory 10 positioned so that the movable actuator is flush against the wearer's face (or nearly so), over the area of the temporalis muscle so that clenching/flexing of the jaw activates the Hall effect sensor 16 or other sensor. Applications for such uses include computer gaming interfaces, which today commonly include head-worn communication equipment. One or more activation accessories 10 configured in accordance with embodiments of the invention may be fitted to such headgear (either when manufactured or as an after-market addition) to provide cursor control capabilities. Conventional wired or wireless communication means may be employed to provide a connection to a console, personal computer, tablet, mobile phone, or other device that serves as the gaming or other host. The use of such human-machine interfaces may find particular application for users that have no or limited use of their hands and afford them a convenient means of interacting with a personal computer, tablet, mobile phone, or similar device.

Further, the controlled device(s) may include one or more microphones. Such microphones may be mounted or integral to a headset and make use of bone conduction transducers for transmission of audio signals. Alternatively, or in addition, activation accessory 10 may be used to adjust the presence, absence, and/or volume of audio played through

one or more earphones or other earpieces. Also, activation accessory 10 may be used to control off-headset equipment, for example, via a wireless transmitter.

One or more of the above-described embodiments may permit signal generation via a control surface that can be activated by direct or indirect force, hinged paddle, touch-sensitive surface, or other tactile actuation device. Devices configured in accordance with these embodiments may employ movable structures (e.g., paddles) that house Hall effect sensors to detect a change in an electromagnetic field when a corresponding magnet is moved in proximity to the sensor. Such devices may be in the form of an accessory to a remote (e.g., hand-held) device or fully integrated into a wearable form factor such as eyewear and headsets. Other sensors, as discussed herein, may also be used.

By providing both a left and right activation means (or any number of them) which may be configured to allow for input of various command sequences (e.g., different numbers of activations similar to single-, double- or other mouse clicks), a user may provide different commands for an associated device. For example, different command activation sequences may be used for zooming a camera, panning a direction in a virtual/visual environment, or a host of other commands to control cameras, audio transmissions (volume up or down), etc. In addition to the foregoing, the use of gyros and/or accelerometers while clenching and holding can allow for selecting and moving objects in the virtual field. This is similar to a click-and-hold followed by movement of a cursor with a mouse or joystick in that it allows a user to move objects (e.g., icons) around on a virtual desktop, to open menus, and to select commands, etc. by clenching and moving one's head. The gyros and/or accelerometers may be incorporated in activation accessory 10 or elsewhere (e.g., in a frame supporting the activation accessory 10).

Thus, systems and methods for operating a controlled device in a hands-free or other manner through volitional jaw clench actions of a wearer, and in particular using an activation accessory for a controlled device that includes a movable actuator, sensor (e.g., a Hall effect sensor), and a communication element have been described. In various embodiments, the present invention improves the functionality of controllable electronic devices by providing improved hands-free and tactile input and control methods that cater to both fully abled and disabled users. Moreover, because the movable actuator of the activation accessory has a range of travel between its fully extended position and fully compressed position, when worn on temple pieces of eyewear and the like the activation accessory accommodates a wide variety of wearers, e.g., those with wide or thin faces, those with or without facial hair, etc. The position of the movable actuator when the activation accessory, or an instrumentality in which it is positioned/included, is donned may contribute to an initial output signal of the Hall effect sensor, but this initial signal can be taken as a baseline value and accommodated when analyzing the output signal of the sensor for commands. Beyond jaw clenching, an input signal can be produced manually by tapping or pressing the activation accessory or an instrumentality in which it is positioned/included at a location that causes the movable actuator to first be compressed then extended, or conversely, for it to first be extended then compressed. The sensor can detect if the tapping or pressing is generated from the right or left side of a head-worn device depending on whether it first detects compression or extension of the movable actuator surface when tapping/pressing force is applied. The movable actuator allows for varying levels of input by detecting

21

movement (e.g., travel, speed, duration, etc.) of the movable actuator caused by clenching, tapping, or pressing, from very light to very hard. While described with reference to eyewear and similar articles, the activation accessory may be worn on/with other wearables that feature a flexible or rigid band (e.g., AR/VR headsets), the inside surface of which defines a plane alongside the wearer's face/head or other wearable bands that define other planes when worn on other parts of the body (e.g., wristbands, etc.). Any such wearable will permit the movable actuator to be moved with respect to the sensor, allowing the sensor to output signals responsive to the wearer moving/flexing associated muscles.

What is claimed is:

1. A wearable device, comprising:

an activation accessory for a controlled device, the activation accessory being integrated into or attached to the wearable device and including a moveable actuator having a range of travel between a fully extended position and fully compressed position, the moveable actuator being biased open from a detection portion of the activation accessory such that when the wearable device is worn on a person the moveable actuator touches the person's body and partially compresses along its length of travel with respect to the detection portion,

wherein the detection portion of the activation accessory comprises a sensor responsive to movements of said moveable actuator, and the activation accessory further includes including:

controller communicably coupled to receive signals from said sensor, said controller having a first output coupled to a control signal interface and including a processor and a memory coupled to the processor and storing processor-executable instructions, which instructions when executed by the processor cause the processor to perform steps including:

receiving, from the sensor, an initial signal generated as a result of partial compressing of the moveable actuator to a position between its fully extended position and fully compressed position when the person dons the wearable device, so as to provide for subsequent adequate movement of the moveable actuator with respect to the detection portion in order to generate commands for the controlled device upon the position of the moveable actuator being affected by volitional actions of the person,

receiving, from the sensor, first input signals produced as outputs of the sensor responsive to movements of said moveable actuator,

evaluating the first input signals to determine whether or not the first input signals represent a command for said controlled device by assessing said first input signals for a signal pattern indicative of the command, and

if said processor determines that the first input signals represent the command, then decoding the command and transmitting an associated control signal to the control signal interface, otherwise not transmitting

22

the control signal and proceeding to evaluate second input signals from the sensor in a like manner as the first input signals; and

a communication element coupled to the control signal interface and adapted to transmit the control signal from the processor to the controlled device, wherein the communication element is one of: a cable having a plug configured to mate with a jack at the controlled device, and a transmitter adapted for radio frequency communication with a receiver at the controlled device.

2. The wearable device of claim 1 wherein the moveable actuator includes a magnet and the sensor is a Hall effect sensor.

3. The wearable device of claim 1, wherein the detection portion is configured to detect varying degrees of movement of the moveable actuator that result in a control signal being generated by said processor.

4. The wearable device module of claim 1, wherein the moveable actuator and the detection portion are connected by a hinge that provides spring bias.

5. The wearable device of claim 1, wherein the moveable actuator and the detection portion are connected by a spring that provides spring bias.

6. The wearable device of claim 1, wherein the moveable actuator and the detection portion are connected by a layer of over molded elastic polymer that provides spring bias.

7. The wearable device of claim 1, wherein the detection portion is removably attached to the wearable device.

8. The wearable device of claim 1, wherein the detection portion is slidably attached to the wearable device.

9. The wearable device of claim 1, wherein the detection portion is integrated as part of the wearable device.

10. The wearable device of claim 1, wherein the moveable actuator is biased with respect to the detection portion to be responsive to input commands generated manually by the person tapping or pressing the wearable device in a manner that causes the moveable actuator to compress against or extend away from an area of the person's body over which the moveable actuator is positioned.

11. The wearable device of claim 1, wherein the moveable actuator is biased with respect to the detection portion to respond to tapping or pressing on a right or left side of the wearable device when the wearable device is being worn on the person's head.

12. The wearable device of claim 1, wherein the initial signal established by partial compression of the moveable actuator resulting from the person donning the wearable device is generated at a point at which the moveable actuator is positioned between its fully extended position and its fully compressed position so as to provide for additional movement of the moveable actuator with respect to the detection portion in order to permit the detection portion to generate signals representing commands for the controlled device upon the position of the moveable actuator with respect to the detection portion being affected by volitional jaw movements of the person.

13. The wearable device of claim 1, wherein the detection portion is attached to the wearable device by an adjustable mounting interface.
